UNITED STATES PATENT OFFICE

159,199

LIGHT FOR SURGICAL AND SIMILAR PURPOSES

Ernest H. Greppin, Rochester, N. Y., assignor to Wilmot Castle Company, Rochester, N. Y., a corporation of New York

Application July 22, 1949, Serial No. 4,067

Term of patent 14 years

(Cl. D48—20)

To all whom it may concern:

Be it known that I, Ernest H. Greppin, a citizen of the United States of America and resident of Rochester, in the county of Monroe and State of New York, have invented a new, original, and ornamental Design for a Light for Surgical and Similar Purposes, of which the following is a specification, reference being had to the accompanying drawings forming part hereof.

In the drawings:

Fig. 1 is a perspective view, seen generally from the bottom, of a light for surgical and similar purposes, showing my new design, with the adjusting handle of the light and the supporting yoke thereof indicated in broken lines;

Fig. 2 is a top plan view thereof, with the adjusting handle indicated in broken lines and with the supporting yoke omitted for the sake of clarity;

Fig. 3 is a view partly in elevation and partly in section taken substantially centrally through the

light, approximately on the line 3—3 of Fig. 2, showing the supporting yoke in broken lines; and

Fig. 4 is a side elevational view of the light, showing part of the adjusting handle and the supporting yoke in broken lines.

The parts shown in broken lines are for illustrative purposes only.

I claim:

The ornamental design for a light for surgical and similar purposes, substantially as shown and described.

ERNEST H. GREPPIN.
